HINGED PROP FOR PICTURE FRAMES

John F. Babbitt, Louisville, Ky., assignor to J. V.
Pilcher Mfg. Company, Incorporated, Louisville,
Ky., a corporation of Kentucky

Application June 1, 1948, Serial No. 30,425

4 Claims. (Cl. 248—33).

1

This invention relates to improvements in a hinge structure for attaching a prop to the backs of picture frames, mirrors and the like.

The main objects of this invention are to provide a highly dependable articulation between a prop and the back of a display device through the use of a minimum quantity of the highest grade material and a small amount of unskilled labor.

Another object of this invention is to provide a superior appearance of the product adverted to above while accomplishing the objects outlined in the preceding paragraph.

Figure 1 is a perspective view of my hinge attached to a prop and the back of a picture frame or other display device.

Figure 2 is a perspective view of the hinge per se on an enlarged scale as it appears after attachment, however, without the back or prop.

Figure 3 is a plan view of the blank, on an enlarged scale, from which the dead leaf of the hinge is formed.

Figure 4 is a plan view of the blank, on an enlarged scale, from which the live leaf of the hinge is formed.

Figure 5 is a fragmentary elevation along the central vertical plane of Fig. 1, on an enlarged scale, to disclose the hinge and the attachment elements to the prop and back members.

Numerals 6, 7, 8, 9 and 10 designate respectively, the back member of a picture frame or the like, the prop therefor, the dead leaf of the hinge, the live leaf of the hinge and the pintle to complete the articulation.

Blank 11 is fabricated from sheet metal with prongs 12, 12 and lip 13. Prior to assembly the prongs are bent at right angles to the body 14 and the lip is curled to provide knuckle 15. These prongs are threaded through correlated slots in back 6 curled and embedded as shown at 16.

Blank 17 is fabricated from sheet metal with two pairs of prongs 18, 18 and 19, 19 and projection 20 having hole 21 cut therein for suspending the complete assembly. These prongs are bent at right angles to body 22 and the remote ends of 18, 19 are curled inwardly to provide knuckles 23, 23 before attachment to prop 1. It should be noted that, when assembled, these knuckles are disposed on the back face of the prop while body 22 lies on the front face and prongs 18, 18 embrace the side edges 24, 24 and are embedded into the back face of the prop. The portions of prongs 18, 19 between the knuckles 23, 23 and body 22, referred to hereinafter as "shanks," have been carefully planned to serve as an abutment for the top end face 25 of the prop and to con-

2

ceal the end portions thereof thus providing protection for the corners, against mechanical abrasion and a neat appealing finish. When the prop is made of cardboard or plywood it is covered with a fabric (not indicated) that also covers prongs 18, 18 and body 22, leaving the shanks exposed.

Again referring to prop 1, it should be noted that in the incident embodiment of this invention the pattern employed is substantially that of the central plane of a truncated cone, therefore, prongs 18, 18 being lodged on inclined planes, would have a tendency to slip away from the desired location if the ends of these prongs were not curled and definitely embedded into the back face of the prop, thus serving a double purpose.

In addition to supplying an eye for suspending the assembly, projection 20 serves as a stop for the prop and being of pliable sheet metal can be bent at will to effect the desired display angle of the picture frame.

Pintle 10 can be applied to effect assembly of the knuckle before or after attachment of the leaves to their respective parts.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

What I claim is:

1. As a new article of manufacture, a hinge for articulating the back of a picture frame or the like to a prop therefor comprising a dead leaf, a live leaf and a pintle; said dead leaf being disposed on one side of the back and having rearwardly projecting prongs extending therethrough and secured to the back face thereof and a forwardly projecting lip curled to provide one knuckle of the hinge; the live leaf applied to the outside face of the prop and having two pairs of rearwardly projecting prongs, one pair of which embrace the side edges of and penetrate the rear face thereof while the ends of the other pair are curled to embrace said rear face of the prop and provide a pair of knuckles of the hinge in alignment with the knuckle of the dead leaf.

2. As a new article of manufacture, a hinge for articulating the back of a picture frame or the like to a prop therefor comprising a dead leaf, a live leaf and a pintle; said dead leaf being disposed on one side of the back and having rearwardly projecting prongs extending through and secured to the back face thereof and a forwardly projecting lip curled to provide one knuckle of

the hinge; the live leaf applied to the outside face of the prop and having a coplanar extension and two pairs of rearwardly projecting prongs, one pair of which embrace the side edges of and penetrate the rear face thereof while the ends of the other pair are curled to embrace said rear face of the prop and provide a pair of knuckles of the hinge in alignment with the knuckle of the dead leaf; said extension being formed and disposed to provide a stop to limit the travel of the prop.

3. As a new article of manufacture, a hinge for articulating the back of a picture frame or the like to a prop therefor comprising a dead leaf, a live leaf and a pintle; said dead leaf being disposed on one side of the back and having rearwardly projecting prongs extending through and secured to the back face thereof and a forwardly projecting lip curled to provide one knuckle of the hinge; the live leaf applied to the outside face of the prop and having two pairs of rearwardly projecting prongs, one pair of which embrace the side edges of and penetrate the rear face thereof while the ends of the other pair are formed to provide a pair of knuckles of the hinge in alignment with the knuckle of the dead leaf and shanks overlying the top edge face of the prop.

4. As a new article of manufacture, a hinge for articulating the back of a picture frame or the like to a prop therefor comprising a dead leaf,

a live leaf and a pintle; said dead leaf being disposed on one side of the back and having rearwardly projecting prongs extending therethrough and secured to the back face thereof and a forwardly projecting lip formed to provide a pintle bearing of the hinge; the live leaf affixed to one face of the prop and having two pairs of rearwardly projecting prongs, one pair of which embrace the side edges of and penetrate the rear face thereof while the ends of the other pair are formed to provide a pair of pintle bearings of the hinge in alignment with the pintle bearing of the dead leaf.

JOHN F. BABBITT.
